D. KOPS.
APPAREL CORSET.
APPLICATION FILED MAY 2, 1919.

1,318,156.

Patented Oct. 7, 1919.

UNITED STATES PATENT OFFICE.

DANIEL KOPS, OF NEW YORK, N. Y.

APPAREL-CORSET.

1,318,156.

Specification of Letters Patent.

Patented Oct. 7, 1919.

Application filed May 2, 1919. Serial No. 294,152.

To all whom it may concern:

Be it known that I, DANIEL KOPS, a citizen of the United States, residing in the borough of Manhattan, city, county, and State of New York, have invented an Improvement in Apparel-Corsets, of which the following is a specification.

This invention relates to an apparel corset and particularly to that type of corset commonly designated a low top corset such as are more or less commonly worn at the present time. In this type of corset, the top thereof is made so low that the upper ends of the front steels lie practically over the pit of the stomach of the wearer, and ordinarily the corsets fit sufficiently tight at the top to cause the upper front edges thereof including the upper ends of the front steels to dig into the pit of the stomach of the wearer when in a sitting or in a leaning forward position, or practically in any usual position. This as will be understood is not only uncomfortable, but oftentimes disadvantageous to the health. The object of my present invention is to overcome this difficulty, and in so doing, in each part of the corset body made in accordance with my invention, I employ stay members running upwardly from the groin section of the corset and preferably diverging toward the upper edge thereof, the same being placed adjacent or in close proximity to the front steel, together with means tending to maintain the lower end of the stay members in a substantially straight position, thereby forcing the upper ends of the stay members and front steels outwardly when in a standing or leaning position, the lower ends of the said members being adapted to lie within the groin section of the body of the wearer when in a sitting position so as to also force the lower ends of the same inwardly and the upper ends together with the upper ends of the front steels outwardly. In this construction also, the upper ends of the front steels are preferably made to terminate an appreciable distance below the upper edges of the garment.

In the drawing:

Figure 1 is a perspective view illustrating an apparel corset made in accordance with this invention.

Fig. 2 is an enlarged elevation of the

inner side of the front portion of the corset garment illustrating my invention.

Fig. 3 is a similar view illustrating another form of the invention, and

Fig. 4 is a cross section on line 4—4, Fig. 3.

Referring to the drawing, and particularly to Figs. 1 and 2, it will be seen that in carrying out this invention, the corset garment made in accordance therewith is preferably constructed in the usual corset body halves indicated respectively at 10 and 11. These corset body halves are provided with eyelets running along the back edges thereof to receive the usual laces for adjusting the garment to position, and in the front of the corset body half 10 there is the usual front steel 12, and in the front of the corset body half 11 a corset steel 13. These corset steels 12 and 13 are provided with the usual clasps 14 by which they are connected to one another.

In each corset body part adjacent the front steel thereof, I employ stay members indicated at 15 and 16 respectively. These stay members are placed in stay pockets formed by suitable lines of stitching which, as shown in Fig. 2, extend from the lower edge of the garment as indicated at 17 to the upper edge thereof, and diverging upwardly, while the respective stay members 15 and 16 placed in these pockets extend from the groin section of the garment as indicated approximately at 18 toward the upper edge thereof so that they also diverge from the groin section upwardly. Attached to the lower edge of the garment at the lower ends of the lines of stitching forming the stay pockets, there is a hose supporter 19 which in use, as will now be understood exerts a tension tending to maintain the lower ends of the stay members in a straight position when the wearer is standing or leaning forward, which naturally will tend to force the upper ends of the stay members outwardly, and when the wearer of the garment is in a seated position, the lower ends of the stay members fit into the groin section of the body, tending to have the same action. Also as indicated in Fig. 2, the upper portion of the garment between the stay members may comprise an insert 20 made of suitable rubber fabric or other

yielding material. It will also be noted, as indicated in this figure, that the upper ends of the corset steels as indicated at 21 terminate an appreciable distance below the upper 5 edge of the garment.

- By reference to Figs. 3 and 4, it will be seen that instead of extending the lines of stitching forming the stay pockets to the lower edge of the corset, the same may be 10 terminated at, or immediately below the groin section as indicated at 22 so that the lower end of the stay members terminate at approximately the section between the lines of stitching forming the pockets therefor as 15 indicated at 23. In this structure, I employ a loop member made of suitable tape or other material as indicated at 24. One end of this loop member is secured to the lower end of the garment and the opposite end to 20 the lower ends of the lines of stitching forming the stay pockets as indicated at 22. Suitably attached to the loop member 24 is a hose supporter member 25. As will now be understood, in this construction the pull 25 or tension by the hose supporter member is directed immediately or approximately at the lower ends of the stay members and the function and action of the parts in the garment thus constructed are similar in all respects to those hereinbefore described in 30 connection with the other form of the invention. That is to say, when in a standing position, the tension of the hose supporter tends to maintain the lower ends of the stays 35 in a straight position thereby forcing the upper ends outwardly, while in a seated position, the lower ends of the stay members fit within the groin section of the wearer, having the same tendency, and in view of 40 the fact that the stay members diverge upwardly in the form of a fan, the entire forward upper edge of the garment including the front steel members adjacent which these stay members are placed is forced outwardly 45 and consequently the tendency to dig into the pit of the stomach of the wearer is overcome.

I claim as my invention:

1. In an apparel corset in which the upper 50 edge of the garment is below the bust and in each corset body part thereof, stay members extending from the groin section and diverging upwardly therefrom toward the upper edge of the garment so that the lower 55 ends of the stays in being maintained in close proximity to the body of the wearer force the upper ends of the stays outwardly to prevent the upper ends of the corset steels from digging into the pit of the stomach of 60 the wearer.

2. In an apparel corset in which the upper edge of the garment is below the bust and in each corset body part thereof, stay members

in close proximity to the front steel and extending upwardly and diverging toward 65 the upper edge of the garment so that when in a seated position, the lower ends of the stays fit into the groin of the wearer, tending to force the upper ends of the stays and corset steels outwardly to prevent the latter 70 from digging into the pit of the stomach of the wearer, and means associated with the said stay members, tending when the wearer of the garment is in a standing position to maintain the lower ends of the stays in a 75 straight position and thus move the upper ends of the stays outwardly.

3. In an apparel corset in which the upper edge of the garment is below the bust and in each corset body part thereof, stay members 80 in close proximity to the front steel and extending upwardly and diverging toward the upper edge of the garment so that when in a seated position, the lower ends of the stays fit into the groin of the wearer, 85 tending to force the upper ends of the stays and corset steels outwardly to prevent the latter from digging into the pit of the stomach of the wearer, a yielding insert member in the upper edge of the garment 90 between the upper ends of the stay members, and means associated with the said stay members, tending when the wearer of the garment is in a standing position to maintain the lower ends of the stay members in 95 a straight position and thus move the upper ends of the stays outwardly.

4. In an apparel corset in which the upper edge of the garment is below the bust and in each corset body part thereof, a corset 100 steel in the front edge terminating an appreciable distance below the upper edge of the garment, and stay members extending from the groin section and diverging upwardly therefrom and terminating at the 105 upper edge of the garment so that the lower ends of the said stays in being maintained in close proximity to the body of the wearer, force the upper ends of said stays outwardly.

5. In an apparel corset in which the upper 110 edge of the garment is below the bust and in each corset body part thereof, a corset steel in the front edge terminating an appreciable distance below the upper edge of the garment, stay members extending from 115 the groin section and diverging upwardly therefrom and terminating at the upper edge of the garment so that the lower ends of the said stays in being maintained in close proximity to the body of the wearer, 120 force the upper ends of said stays outwardly, and a yielding insert member in the upper edge of the garment between the upper ends of the stay members.

Signed by me this 28th day of April, 1919. 125
DANIEL KOPS.
